UNITED STATES PATENT OFFICE

159,242

HEATER

De Witt H. Wyatt, Columbus, Ohio

Application November 12, 1948, Serial No. 149,586

Term of patent 14 years

(Cl. D81—10)

To all whom it may concern:

Be it known that I, De Witt H. Wyatt, a citizen of the United States, residing at Columbus, county of Franklin, State of Ohio, have invented a new, original, and ornamental Design for a Heater, of which the following is a specification, reference being had to the accompanying drawings, forming a part thereof.

Figure 2 is a side perspective view of the heater, showing one side thereof, it being understood that the opposite side is substantially like the side shown.

I claim:

The ornamental design for a heater, substantially as shown and described.

DE WITT H. WYATT.
